DESIGN FOR A TRAY OR SIMILAR ARTICLE

Samuel S. Schmidt, York, Pa., assignor to Grey Iron Casting Company, Mount Joy, Pa., a corporation of Pennsylvania

Application March 26, 1946, Serial No. 127,964

Term of patent 14 years

(Cl. D44—10)

To all whom it may concern:

Be it known that I, Samuel S. Schmidt, a citizen of the United States, residing in York, county of York, State of Pennsylvania, have invented a new, original, and ornamental Design for a Tray or Similar Article, of which the following is a specification, reference being had to the accompanying drawing, forming a part thereof.

Fig. 1 is a perspective view of a tray or similar article showing my new design; and

Fig. 2 is an end view of the tray or similar article shown in Fig. 1.

The opposite side of the perspective view is substantially the same as that disclosed. The opposite end is substantially the same as the end disclosed.

I claim:

The ornamental design for a tray or similar article, substantially as shown and described.

SAMUEL S. SCHMIDT.
